UNITED STATES PATENT OFFICE.

HORACE E. HENWOOD, OF NEW YORK, N. Y.

ACETYLENE-GAS GENERATOR.

1,246,266.

Specification of Letters Patent.

Patented Nov. 13, 1917.

Application filed February 1, 1912, Serial No. 674,648. Renewed March 7, 1914. Serial No. 823,245.

To all whom it may concern:

Be it known that I, HORACE E. HENWOOD, a subject of the King of Great Britain, residing at New York city, in the county and 5 State of New York, have invented certain new and useful Improvements in Acetylene-Gas Generators, of which the following is a clear, full, and exact description.

This invention relates to acetylene generators of the automatic gravity feed type for use with the smaller sizes of carbid.

The objects of the invention are to simplify, improve and cheapen the cost of production of such generators, at the same time 15 to increase the efficiency, to provide an improved carbid filling means in conjunction with a feed device and diaphragm for controlling the same, and to assure the stability of the gas pressure, in order to prevent fluctuations of the light, by means of improved 20 constructions of the feed device and guiding means therefor.

The scope of my invention will be pointed out in the claims.

25 In the accompanying drawings:

Figure 1 is a side elevation of my improved generator with a portion broken away.

Fig. 2 is a central vertical sectional view 30 of the carbid chamber.

Fig. 3 is a top plan of the filling device with the closure top removed.

Fig. 4 is a cross section on line 4—4 Fig. 2.

Fig. 5 is a side elevation with a guide in 35 section of a modified form of feed device.

Fig. 6 is a view similar to Fig. 5, showing a still further modified form of feed device.

Fig. 7 is a view similar to Figs. 5 and 6 40 of a feed device, having a different construction from those of Figs. 5 and 6.

Fig. 8 is a side elevation similar to Figs. 5 and 6 and 7 of a feed device provided with lateral grooves.

Fig. 9 is a view similar to Fig. 8 with feed 45 devices provided with oblique grooves.

As shown in Fig. 1, 1 is the body of the generator adapted to contain the water, and it is provided with a depending skirt 2 enclosing the slanting bottom 3. At the apex 50 of the slanting bottom 3 I secure by a removable nut the pipe 4 leading to the valve 5. At the side of the casing, or chamber, I provide a water gage 6, and preferably on the opposite side a water receiving hopper 55 7, which may be connected by a flexible tube 8 with the inlet 9 for the valve. In order to

fill the container with water the flexible tube is fastened in place, and water poured into the receiving hopper until the desired level is found to be reached. Then the valve is 30 closed.

Above the water container 1 is a chamber 9^a for the carbid, having a conical or hopper bottom terminating in an aperture for the feed of the carbid. In the bottom I insert 65 pipes 10 leading preferably from the angles formed by the slanting walls and sides within the water chamber, such pipes 10 leading downwardly within the carbid chamber toward its center. These pipes are embodiments of means other than the feed aperture 70 for conducting the gas from the water chamber through the conical bottom of the carbid receptacle into the interior of the latter at points adjacent its lowest portion, so that the gas receives the benefit of the maximum drying action in passing through the carbid, without, however, slaking the carbid immediately adjacent the feed aperture and feed device coöperating therewith. 75

I have shown the feed aperture as formed in a separate bushing 11 threaded into a circular central flange of the sheet metal portion of the bottom of the carbid receptacle. With the feed aperture is associated 80 a sleeve or guide extension 13, having lateral ports for the passage of the carbid. This guide is shown as united with the bushing 11 and therefore carried by the bottom of the carbid receptacle. In the present instance the guide extension projects downward from the bottom, so as to hold the feed device (hereinafter described) central 85 when depressed so that its tapered portion stands within the feed aperture. In the 90 normal non-feeding position a cylindrical end 14 of a feed plug occupies a position as shown in Fig. 2 within the orifice of the bushing. The feed plug shown in Fig. 2 is provided with a conical portion 15 and is 95 carried at the end of a rod or shaft 16. The rod 16 is secured at its upper end by means of a threaded bushing 17 with a filling head 18 provided with feed orifices 19, on each side of the rod, and a center orifice 100 20 connecting therewith, normally covered and protected and closed by a thumb nut 21. The filling head is connected with the carbid chamber or upper walls of the generator by an annular diaphragm 22 fastened to the bottom of the filling head by a 105 ring plate 23, and securing screws 24, and 110

to the carbid container by screws 25 secured to an inwardly turned flange 26 of the carbid container, such flange being of material width to permit the securing of the gage 5 pipe 27 and the outlet pipe 28 to the upper part of the container. A circular dome like structure 28^a is also secured to the inturned flange, and it is provided with a central opening through which the head may project and reciprocate, but through which it may not be projected due to a beaded skirt 29 at the bottom of the carbid charging bead.

Projecting arms 39 on the carbid head are 15 connected by springs 31 to the flanges 32 between the carbid container and the water receptacle, where they are secured by bolts 33.

The outlet pipe 34 may lead from the top 20 of the carbid receptacle, which outlet may be surmounted by a safety valve 35 of any construction. I have shown it as consisting of a piston 36 and the spring 37, encircling it within a cylindrical shell 38 so that upon 25 the upward motion of the piston the orifice 39 will be uncovered to reduce the pressure. A hand rod 40 may be provided to test the working condition of the valve, and to open the valve by hand to let the gas escape from 30 the generator into the open air outside the building instead of into the room when recharging the carbid hopper.

As shown in Fig. 2, the feed plug has a general conical configuration, and is there 35 shown with a straight cylindrical closure part, and a plain conical upper part. This form of plug is claimed specifically in my copending application, Serial No. 823,247, filed February 1, 1912.

40 The various forms of feed plug, it will be observed, possess cylindrical lower or closure portions and upwardly tapering feeding portions. When the latter portions are interrupted or tapered in gradations, as in 45 Figs. 5, 6 and 8, for example, the feed of the carbid is more even and fluctuations in the gas pressure are less than when smooth or substantially continuous sides are used, as in Figs. 2 and 7. Particularly good results 50 are obtained with constructions such as shown in Figs. 5 and 8, wherein the tapered portions present a series of comparatively abrupt shoulders to the descending carbid. In acetylene generators it is very difficult to 55 obtain an automatic control which avoids fluctuation in the light secured, and the design of the feed plug therefore becomes of substantial importance.

As shown in Fig. 5, instead of the plain 60 conical upper portion I may provide a series of cylinders 41 above the closure cylinder 42, diminishing in diameter until they reach the rod to which the closure plug is secured.

In Fig. 6, in addition to the closure cylinder 43 I have shown instead of a plain conical upper portion a series of different diameter rings 44, each having concave sides, their diameters reducing until they reach their supporting rod. 70

In Fig. 7, in addition to the cylindrical closure 45, instead of the conical portion of the plug, I may form the portion between the closure cylinder and the rod with smooth sides, concave and of the same diameter if 75 desired at the rod as at the cylinder.

In Fig. 8, in addition to the cylinder 46, I may provide a series of grooves 47 on the conical portion of the plug, such grooves being shown as horizontal. 80

In Fig. 9, in addition to the cylindrical closure portion 48 I may form the conical feeding portion with oblique grooves 50, all for the purpose hereinafter described. 85

In operation, after water has been placed in the lower chamber and carbid in the upper, and the thumb screw for the carbid feeding head fastened down, the side springs will tend to lower the charging head and its diaphragm, and thereby move the cylindrical closure plug of whatever type may be used below the orifice at the bottom of the carbid chamber, thus causing the carbid to pass out and through the ports in the guide in a fine continuous stream, generating gas, which will pass through the pipes in the bottom wall of the carbid receptacle, through the carbid and create a pressure until such pressure is sufficient to expand and raise the diaphragm to cut off the further feed of the carbid. Upon the use of the gas the pressure will be depleted, and the feed plug again dropped, thus automatically keeping up the supply of gas, and preventing undue fluctuation. 95

In carrying out this invention, details of construction may be varied from those shown, and yet the essence of the invention be retained; some parts might be employed without others, and new features thereof 100 might be combined with elements old in the art in diverse ways, although the herein described type is regarded as embodying substantial improvements over such modifications. 110

As many changes could be made in the above construction, and many apparently widely different embodiments of the invention could be made without departing from the scope thereof, it is intended that all matter contained in the above description or shown in the accompanying drawings shall be interpreted in an illustrative and not in a limiting sense. 120

It is furthermore desired to be understood that the language used in the following claims is intended to cover all the generic and specific features of the invention here- 125

in described, and all statements of the scope of the invention which as a matter of language might be said to fall therebetween.

I claim as my invention:

5. 1. In an acetylene gas generator the water chamber, the carbid receptacle, a conical bottom for the carbid receptacle forming the top of the water chamber, a feeding plug at the center of said conical bottom, tubing
 10 to admit gas to the carbid receptacle to a point adjacent to said feeding plug, a shaft for said feeding plug, a filling head secured to the shaft and a diaphragm securing said filling head to the receptacle.
15. 2. In an acetylene gas generator having a filling head, and a diaphragm, a carbid receptacle to which the diaphragm is also secured, a water chamber below the carbid receptacle, a conical bottom for the carbid receptacle and openings therethrough for the passage of gas, a shaft secured to said filling head and having a feed plug in part cylindrical and in part of general conical shape, a bushing for the feed plug having a central
 20 aperture and a guide projecting into the water chamber having side ports in its wall.
3. In an acetylene gas generator, having a carbid receptacle, a water chamber below the carbid receptacle, a conical bottom for the carbid receptacle, a shaft and means for reciprocating said shaft, a feed plug in part cylindrical and in part of general conical shape, a bushing for the feed plug having a central aperture and a guide having side
 25 ports in its wall.
4. In an acetylene gas generator, having a carbid receptacle, a water chamber below the carbid receptacle, a conical bottom for the carbid receptacle, a shaft and means for reciprocating said shaft, a feed plug in part cylindrical and in part of general conical shape, a bushing for the feed plug having a central aperture and a guide having side ports in its wall, said guide projecting into
 30 the water chamber.
5. In an acetylene gas generator, a carbid receptacle, a water chamber and means for feeding the carbid, a diaphragm controlling said means, a filling head carried by the diaphragm having a closure cap.
6. In an acetylene gas generator, a carbid receptacle, a water chamber and means for feeding the carbid, a diaphragm controlling said means, a filling head carried by the diaphragm having a closure cap, said filling head serving to connect the feeding means and the diaphragm.
7. In an acetylene generator having a carbid receptacle having an aperture in its bottom, a water chamber below the carbid receptacle, a reciprocating head, a flexible diaphragm connecting said head to the carbid receptacle, a shaft connected to the reciprocating head, a feed plug in part cylindrical and in part of a general conical shape connected to said shaft and controlling the aperture in the bottom of the carbid receptacle, and a guide extension of said aperture having side ports in its wall.
8. In an acetylene generator, a water reservoir, a carbid receptacle above the water reservoir, a central aperture in the bottom of the carbid receptacle, a feed plug operating in said aperture, a reciprocating shaft controlling said feed plug, a reciprocating head secured to said shaft, a means for controlling the reciprocating head, a flexible diaphragm securing said head to the carbid receptacle, said head having passages through it for charging the carbid receptacle with carbid, and a closure stopper for said passages.
9. In an acetylene generator, a water reservoir, a carbid receptacle, a central aperture in the bottom of the said receptacle, a reciprocating shaft controlling said feed plug, a reciprocating head secured to said shaft, a means for controlling said head, a flexible diaphragm securing the reciprocating head to the carbid receptacle, and a means for charging the carbid receptacle with carbid through a central orifice of the flexible diaphragm.
10. An acetylene generator having a carbid receptacle, a water reservoir below the carbid receptacle, a feed plug controlling the passage of carbid from the carbid receptacle to the water reservoir, an upwardly extending shaft connected to said feed plug, a diaphragm, and a filling head mounted in the central part of the diaphragm, connected to the upper part of said shaft and accessible at the top of the receptacle.
11. An acetylene generator having a carbid receptacle, a water reservoir below the carbid receptacle, a feed plug controlling the passage of carbid from the carbid receptacle to the water reservoir, an upwardly extending shaft connected to said feed plug, a filling head connected to the upper part of said shaft and operating through the top of the receptacle, and a diaphragm connected with the head.
12. In an acetylene generator, the combination of a carbid receptacle, a water reservoir, a feed plug, a filling head connected with the feed plug and reciprocating in an opening in the top of the generator, and a diaphragm connected with the head.
13. In an acetylene generator, a water chamber, a carbid receptacle having a conical bottom terminating in a feed aperture, a diaphragm, a vertically movable feed plug connected with the diaphragm and having a lower cylindrical portion joining an upwardly tapering portion, and an extension guide projecting downward from the apertured lower end of said conical bottom and

provided with lateral openings for the passage of the carbid.

14. In an acetylene generator, a water chamber, a carbid receptacle having a conical bottom terminating in a feed aperture, a feed device controlling said aperture, and means other than the feed aperture for admitting the gas from the water chamber through the bottom of the carbid receptacle into the

said receptacle adjacent the lowest portion 10 thereof.

Signed at New York city, New York, this 30th day of January, 1912.

HORACE E. HENWOOD.
